1 Claim. (Cl. 248—18)

The invention relates to an air conditioning unit and particularly to a means for mounting the fan and motor assembly within the unit.

Conventional air conditioning apparatus is by its very nature a source of noise and vibration. The primary sources of noise and vibration emanating from air conditioning apparatus include the fan or fans, the drive motor or motors therefor and the compressor and its drive motor. Since the air conditioning apparatus or a portion thereof may be within the enclosure being conditioned, noise and vibration attributable to the air conditioning apparatus, particularly noise and vibration emanating from that portion located within the confines of the enclosure, is objectionable and hence is to be avoided or isolated in so far as practicable.

For purposes of description, an air conditioning unit may be divided into a condenser section and an evaporator section. In an air-to-air type of unit, the condenser section communicates with the out-of-doors either through physical placement outside or by means of suitable duct work. The evaporator section communicates with the enclosure being conditioned either through physical placement therein or by means of suitable duct work. In this type of unit both the condenser section and the evaporator section rely on the circulation of air for their operation and accordingly both sections normally are provided with a fan. A suitable power means, for example, a motor and a suitable drive means between the motor and fan, for example, a belt and pulley arrangement, are provided to drive the fan. Since the evaporator section may be located within the confines of the enclosure or, if not within, communicating therewith by suitable duct work which it is understood may transmit noises originating in the evaporator section into the enclosure, the evaporator fan and drive motor therefor are of particular concern as a source of noise and vibration.

Heretofore, the evaporator fan has been driven by a relatively low speed four-pole electric motor rigidly attached to the air conditioning unit structure within the evaporator section. A typical four-pole motor speed is 1,750 r.p.m. Recent practice, however, employs a two-pole electric motor operating at approximately twice the r.p.m. of the heretofore mentioned four-pole motor, typically 3,500 r.p.m., to drive the evaporator fan. As in the case of the four-pole motor, a rigid attachment of the two-pole motor to the air conditioning unit structure is provided.

Vibration resulting from unbalance in the rotating parts of the evaporator fan motor and the drive between the motor and fan, heretofore not particularly significant at the relatively low speed of the four-pole motor, is magnified by the doubled rotational speed of the two-pole motor. This vibration, now at a higher frequency, more closely approaches the natural resonance of the various structural parts and panels of the air conditioning unit. As may be understood, panels of a given area are more efficient noise radiators at higher frequencies resulting in an increased noise level. An increase in the number of resonating parts and panels increases the noise level. The noise itself is more disturbing because of the sensitivity of the human ear to higher frequency noises. Further, because of the rigid attachment of the evaporator fan motor to the unit, vibration originating in the motor and drive may be transmitted in varying degrees to other

2

parts of the air conditioning unit with deleterious effects. Particularly susceptible to vibration induced fatigue are the various refrigerant piping connections.

With these considerations in mind, it is a principal object of this invention to provide an improved means for supporting a fan assembly in an air conditioning unit.

It is a further object of this invention to provide a novel mounting structure for the fan assembly of an air conditioning unit effective to resiliently yet accurately position the fan assembly in operative relationship with respect to the unit.

It is an additional object of this invention to provide a unique mounting structure effective to position the fan and motor assembly within an air conditioning unit so that vibrations emanating from the fan and motor assembly are absorbed to thereby prevent transfer thereof to the air conditioning unit.

This invention relates to an air conditioning unit including a housing, a compressor, a condenser section including a fan, an evaporator section including a fan, the evaporator fan being rotatably mounted on an auxiliary frame, a drive motor on said auxiliary frame operatively connected to the evaporator fan, and means to position the auxiliary frame in the enclosure including a plurality of mounting rods fixedly attached to the auxiliary frame, a plurality of mounting brackets fixedly attached to the enclosure and adapted to receive the mounting rods therethrough, a resilient spacer for each of the fan mounting brackets adapted to receive a mounting rod therethrough, one end of the spacer being adapted to abut its respective bracket, a spring adapted to surround a portion of each of said resilient spacers, one end of the spring abutting a portion of each spacer adjacent said one end thereof, a retaining member adapted to receive each of said mounting rods therethrough and to abut the opposite end of each spring and an adjustable locking device on each of the mounting rods adapted to contact the opposite side of the retaining member to adjust spring tension.

The attached drawing illustrates a preferred embodiment of the present invention, in which:

FIGURE 1 is a plan view, partially in section, illustrating an air conditioning unit embodying the present invention;

FIGURE 2 is a cross-section taken along line II—II of FIGURE 1 showing applicant's novel mounting means; and

FIGURE 3 is an enlarged sectional view of applicant's novel mounting structure.

Referring to the drawings, numeral 1 designates generally an air conditioning unit. Preferably, the unit comprises an indoor compartment 2 and an outdoor compartment 3 separated by a partition 4. Partition 4 is provided with a suitable insulation 7 whereby indoor compartment 2 is thermally isolated from outdoor compartment 3.

Outdoor compartment 3 includes a compressor 8 positioned therein. A suitable motor 9 is provided therefor. Outdoor coils 11, 12 are positioned adjacent openings 13, 14 respectively in the opposite sides 5 of the outdoor compartment 3. A fan 18 having a drive motor 19 operatively connected thereto is secured by suitable means to the inside surface of top panel 20 of outdoor compartment 3. An opening 21 having a suitable grill is provided in top panel 20 of compartment 3 adjacent fan 18.

It is understood that fan 18 draws outside air through the openings 13, 14 across coils 11, 12. The air exhausts to the atmosphere through opening 21 in the top panel 20.

The indoor compartment 2 includes an indoor coil 30 positioned adjacent opening 31 in end panel 32. A fan

scroll 36 is fixedly positioned adjacent coil 30 in the indoor compartment 2 by suitable means (not shown). A diffuser 37, rigidly attached to fan scroll 36, communicates with the area to be conditioned. A fan 35 is positioned within the scroll 36. A drive motor 39 is operatively connected to fan 35. The construction and mounting of fan 35 and motor 39 will be more particularly described hereinafter. Scroll 36 is provided with suitable inlets 40.

Air is drawn through opening 31 across the indoor coil 30 which serves to condition the air. The conditioned air then passes into inlets 40 of scroll 36. Fan 35 discharges the conditioned air through diffuser 37 into the area to be conditioned.

Diffuser 37 may communicate directly with the area to be conditioned or indirectly by means of suitable duct work. The inlet opening 31 may communicate with the atmosphere whereby fresh air is introduced into the compartment 2 for conditioning or it may communicate with the area conditioned either directly or by means of suitable duct work whereby air from the area conditioned is introduced into the compartment 2 for conditioning. Adjustable dampers (not shown) may be provided to permit varying mixtures of indoor and outdoor air to be introduced into inlet opening 31 for conditioning.

Coils 11, 12 and 30 and compressor 8 are operatively connected to provide a closed circuit for a suitable refrigerant. A suitable expansion device is included in the refrigerant circuit.

If the unit 1 functions to cool the area to be conditioned, indoor coil 30 serves as the evaporator and outdoor coils 11, 12 serve as the condenser. If the unit 1 functions to heat the area to be conditioned, indoor coil 30 serves as the condenser and outdoor coils 11, 12 serve as the evaporator. Motors 9, 19 and 39 are suitably connected to a source of electric power. Suitable controls for the unit 1 are also provided.

Fan 35 and drive motor 39 therefor are included in subassembly 34 attached to diffuser 37 and partition 4 within the indoor compartment 2 in a manner to be more fully explained. In the embodiment shown, fan 35 includes two fans 45 and 46 fixed to a common drive shaft 47. As may be understood, fan 35 may comprise one or more fans. The opposite ends of drive shaft 47 are rotatably supported in bearings 49, 50 fixedly attached to the side members 51, 52 respectively of an auxiliary or sub-frame 55.

In the embodiment shown, the auxiliary frame 55 is generally U-shaped with a base member 56 rigidly attached to the aforementioned side members 51, 52 to form the U-shape. It is understood that auxiliary frame 55 may be of any desired configuration, for example, trapezoidal. Brace members 59 are fixedly attached between each of the side members 51, 52 respectively and the base member 56.

A motor base plate 61 having fan motor 39 rigidly attached thereto is provided. Pivot means 62 on each side of the motor base plate 61 cooperate with brace member 59 and auxiliary support 63 to pivotally mount motor base plate 61 on the auxiliary supporting frame 55. A support member 65 is pivotally attached to brace member 59 so as to extend outwardly therefrom. A slot 66 is provided in the remote end of support member 65. A bolt 67 slidably receivable in the slot 66 is attached to the edge of plate 61 remote from the aforesaid pivotal attachment. The portion of bolt 67 extending beyond slot 66 is suitably threaded.

The shaft of motor 39 is provided with a pulley 69 fixedly attached thereto. A cooperating pulley 70 is fixed on fan shaft 47. Belt 71 drivingly interconnects the motor pulley 69 with the shaft pulley 70.

It is understood that the pivotal mounting of motor plate 61 on auxiliary frame 55 permits adjustment of the center to center distance between the motor pulley 69 and the fan pulley 70 and accordingly permits adjust-

ment of the tension of belt 71. A suitable threaded locking means, for example, a nut (not shown) is adapted to cooperate with the threaded portion of bolt 67 to fixedly position bolt 67 relative to slotted support member 65 whereby an adjusted belt tension may be maintained.

In order to position the subassembly 34 within the unit, mounting rods 75 are suitably fixed to the auxiliary frame 55 at each of the corners thereof. Ends 90 of rods 75 are suitably threaded. Mounting brackets or plates 74, 76 are provided. Brackets 74 are fixedly attached by suitable means (not shown) to the outside casing of diffuser 37. As noted heretofore, diffuser 37 is rigidly attached to fan scroll 36. The fan scroll and diffuser unit is rigidly positioned within indoor compartment 2 by suitable means (not shown). Brackets 76 are similarly fixedly attached to partition 4 of enclosure 1. Mounting brackets 74, 76 are each provided with a cylindrical boss or protuberance 95, the end of which is open at 77. Mounting rods 75 are adapted to extend through openings 77 whereby the sub-frame 55 may be positioned within the enclosure 1.

Referring particularly to FIGURE 3 of the drawings, resilient spacers 80 each having a central bore 81 therethrough adapted to receive rods 75 are provided. Spacers 80 may be composed of rubber or other suitable resilient material. A cylindrical recess 84 is provided in one end 79 of each of the spacers 80. Spacers 80 may be of a generally cylindrical construction having a stepped portion 92 of a radius slightly greater than the main portion 93. A second stepped portion 94 including the end 79 adjoins stepped portion 92 and is of a greater radius. The surface 83 between the stepped portions 92, 94 constitutes an abutment or land against which one end of spring 85 bears. As may be understood, end 79 of resilient spacers 80 is adapted to abut its respective mounting plate 74 or 76, cylindrical recess 84 receiving the mounting plate protuberance 95. The resilient portion of spacer 80 between surface 83 and end 79 provides high frequency vibration isolation.

A spring 85 adapted to surround each resilient spacer 80 is provided. One end of spring 85 abuts surface 83 of spacer 80. Retaining member 86 having a hole 87 therein adapted to receive mounting rod 75 abuts the opposite end of spring 85. Member 86 may be cup shaped so that the opposite end of spring 85 may be received in and located by the cup shaped portion of member 86.

The sub-frame 55 is slidably positioned within indoor compartment 2 to fixed diffuser 37 and partition 4 by inserting mounting rods 75 into holes 77 of brackets 74, 76. Resilient spacers 80 are next placed on each of the mounting rods 75 so that the end 79 of each spacer abuts its respective mounting bracket 74, 76. As noted the protuberance 95 of each of the brackets 74, 76 is received in the cylindrical recess 84 of its respective spacer 80 to thereby locate and position spacer 80. Spring 85 is positioned over each spacer 80 so that one end thereof abuts land portion 83 of resilient spacer 80. The opposite end of spring 85 abuts retaining member 86. Nuts 91 are provided which cooperate with threads 90 of each of the rods 75 to lock the assembly together. As may be appreciated, nuts 91 may be adjusted to provide proper vertical alignment of the subassembly 34 with respect to the fan scroll 36.

Springs 85 are selected to provide a proper degree of static deflection. The amount of static deflection selected is unusually large, for example, approximately one-half inch. This large amount of initial static deflection permits applicant's unique mounting to absorb all but the very lowest vibrational frequencies of the subassembly 34. As may be understood, excessive displacements of the subassembly 34 are absorbed through contact of the retaining member 86 with spacer 80.

That portion of spacer 80 between each spring 85 and its respective mounting bracket 74, 76 prevents metal to

metal contact between each bracket and its respective spring and provides high frequency vibration isolation. The spacer also prevents metal to metal contact between each mounting rod 75 and its respective bracket 74, 76. Thus, noise due to relative movement between the bracket and spring and between the mounting rod and the bracket is eliminated.

Resilient spacers 80 are located against lateral movement through the cooperation of mounting plate protuberance 95 with cylindrical recess 84. The cooperation of bore 81 of resilient spacer 80 with its respective mounting rod 75 limits lateral movement of the subassembly 34 relative to the indoor compartment 2. As may be noted in the drawings, the bore 81 of each resilient spacer 80 is of slightly larger diameter than its respective mounting rod 75 so as to provide a clearance therebetween. This clearance between bore 81 and its respective mounting rod 75 permits relative movement between the resilient spacer 80 and the rod 75 in a vertical direction but limits lateral movement of mounting rod 75 relative to the resilient spacer.

It may also be noted that the resiliency or strength of the various springs 85 may vary dependent upon the weight supported by each spring in order that all mounting points have the same degree of deflection to insure movement of the fan and motor subassembly in a single plane. Movement of the subassembly 34 in a single plane, that is a direction perpendicular to the axis of the fan scroll 36 obviates the possibility of contact between the revolving fans 45, 46 and the stationary scroll 36. Lateral movement of the subassembly 34 is restricted through the cooperation of openings 81 in resilient spacers 80 with rigid mounting rods 75. It is appreciated that the resilient spacers 80 are firmly positioned against lateral movement through contact of bracket protuberance 95 with spacer recess 84.

While I have described a preferred embodiment of the present invention, it will be understood that the invention is not limited thereto since it may be otherwise embodied within the scope of the following claims.

I claim:

A support for resiliently positioning a fan and motor

unit in an air conditioning apparatus housing comprising a rod-like member secured to said fan and motor unit, a plate-like bracket having a generally cylindrical outwardly projecting bracket part and an opening therethrough secured to said air conditioning apparatus housing, said bracket opening being coaxial with said projecting bracket part and dimensioned to permit free movement of said rod-like member therethrough, a generally cylindrical resilient member engaging said bracket, the portion of said resilient member engaging said bracket having a generally cylindrical recess for snugly receiving said bracket projecting part to inhibit lateral movement between said resilient member and said bracket, said resilient member having an opening therethrough coaxial with said recess and dimensioned to permit free movement of said rod-like member therethrough, said cylindrical resilient member having a first stepped portion and a second stepped portion spaced therefrom, the second stepped portion being adjacent the bracket and having an outer dimension greater than the outer dimension of the first stepped portion, the portion of the resilient member between said first and second stepped portions forming an abutment, a spring around said resilient member first stepped portion in engagement with resilient member abutment, and adjustable connecting means between said rod-like member and said spring for selectively controlling the dampening response of said support.
